BAG FASTENER

Filed June 13, 1922

Inventor
William C. Hiering
By his Attorney
Frank C. Fieckst!

UNITED STATES PATENT OFFICE.

WILLIAM C. HIERING, OF NEWARK, NEW JERSEY, ASSIGNOR TO THE J. E. MERCOTT CO., OF NEWARK, NEW JERSEY, A CORPORATION OF DELAWARE.

BAG FASTENER.

Application filed June 13, 1922. Serial No. 567,943.

To all whom it may concern:

Be it known that I, WILLIAM C. HIERING, a citizen of the United States, residing at Newark, in the county of Essex and State 5 of New Jersey, have invented certain new and useful Improvements in Bag Fasteners, of which the following is a specification.

The principal purpose of this invention is in the provision of a novel form of snap 10 fastener, applicable to the metal frames of hand bags, purses and like impedimenta commonly carried by women, and which are further secured when in a closed position by a locking latch interengaged in such 15 manner as to defy release of the fastener prior to removal of the latch.

A further object is to provide such fasteners with ready means for operation and which permit operative engagement irrespective of the position of the latch.

Another aim is to produce a fastener of pleasing appearance and which can be manufactured at a moderate cost.

These objects are attained by the novel 25 construction, combination and arrangement of parts hereinafter described and shown in the accompanying drawing, forming a material part of this disclosure, and in which:—

30 Figure 1 is a side elevational view showing an embodiment of the invention as applied to a conventional type of bag frame, the raised position of the latch being shown in broken lines.

35 Figure 2 is an enlarged fragmentary plan view of the same.

Figure 3 is a further enlarged transverse sectional view taken on line 3—3 of Fig. 2.

The bag frame, as shown, consists of a 40 pair of like channel units, 5 and 6 hingedly engaged at the ends of their parallel side members by pins 7 riveted to form substantial joints and adapted to fold closely adjacent, the fabric of the container being 45 secured as usual in the frame.

On the outer corners of one of the frame sides as 6 are secured eyes or rings 8 to which are attached any of the usual handles, flexible or rigid as preferred.

50 Also on the same frame side, central of its longitudinal bar portion, is a rigid upstanding closed loop catch 9, generally oval in shape, enclosing an opening 10 and presenting bosses 11 and 12 at its respective ends along a median line, the boss 11 being

so shaped as to present a stop or seat 13 on its outer edge.

Pivoted axially of the boss 12 are the ends of a flat U-shaped locking latch 14, its inner sides being in close proximity to the outer 60 sides of the catch 9, over which the latch may swing upon its pivot 15 until the outer curved portion or bend 16 of the latch contacts with the seat 13.

A rolled extension or knob 17 is formed 65 on the outer side of the bend 16 to act as a handle in operating the latch.

On the outer side of the latch, opposite the mating frame member, is a detent 18 formed by pressing the material sharply 70 outward at an angle near its lower edge, the purpose of the detent being apparent further on.

Rigidly secured to the other frame side 5, at a point directly opposite the fixed catch 75 9, is a footing 20 from which projects a bar 21 bent at a right angle toward the loop and having fixed permanently upon it a solid knob or sphere 22, so shaped, positioned and dimensioned as to pass through the 80 opening 10 upon the application of force sufficient to spring the sphere outward as it passes over the lower element of the catch 9, thereafter hugging the same and drawing the frame sides into close contact 85 due to the cam effect of the sphere in contact with the catch as urged by the resiliency of the bar 21.

While this device is in itself an efficient and positive snap fastening holding the 90 frame sides in proper closed relation, it may happen that the knob should come in accidental forceful contact with an adjacent article and thus be released, allowing the container to inadvertently open, which condition is avoided in the following manner.

The sphere 22 is formed with an undercut recess 23 at its rear, one of the walls 24 of which extends inward on the plane of the angular portion of the bar 21 to about one 95 half the diameter of the sphere, intersecting the other wall 25, disposed at an angle approximately thirty degrees.

Thus when the sphere 22 is in an engaging position, the latch 14 is pressed down 105 to rest upon the seat 13, at which time the detent 18 will have engaged the outer edge of the wall 25 of the sphere, forced its way into the cavity 23 and become spring locked therein, preventing raising the latch 110

except by the application of force applied to the knob 17, and obviously locking the sphere against retraction until the latch be raised, as the body of the latch is interposed in such manner as to prevent withdrawal of the sphere.

It may be pointed out however that the sphere can be passed through or into the opening 10 in the fixed catch irrespective of the position of the latch, for if the latter should drop down into a locking position, when the frame sides are apart, it will be raised by entering the sphere, the curved surface of which acts as a cam upon being forced into the opening.

As changes of construction could be made within the scope of the invention, it is intended that all matter contained in the foregoing description or shown in the accompanying drawings shall be interpreted as illustrative and not in a limiting sense.

Having thus described my invention, what I claim as new and desire to secure by Letters Patent, is:—

1. A fastener for hinged frame members comprising a rigid enterable element on one of said members, a yielding entering element on the mating member, said elements being adapted for interlocking engagement and a forked latch pivoted at the end to straddle said enterable element and adapted to retain the entering element therein.

2. A fastener for hinged frame members comprising a projecting element on each frame member co-acting to hold the members together, a solid sphere carried by one of said elements, an auxiliary latch member

pivoted on one of said elements to enclose the same and lock the other element in engaged position, said solid sphere having an angular recess and a detent on said latch engageable with the recess in said last named element.

3. A fastener for hinged frame members comprising a catch member mounted on each of said frame members for mutual co-operation, said catch members being adapted to engage each other for holding the frame members together, a forked latch pivoted at one end to swing over the sides of one of said catch members confining the other member thereto, a stop limiting the movement of said latch, a detent formed on the side of said latch engageable in a recess formed in one of said catch members, and a knob associated with said latch whereby it may be operated.

4. A fastener for hinged frames comprising a thin upstanding plate element fixed on one of the frame members, said element containing an opening, a yieldingly mounted spherical element on the other frame member, said spherical element containing an angular recess in its rear surface, a forked latch pivoted to straddle said plate, and a detent carried by said latch engageable in the mentioned recess in said spherical element.

This specification signed and witnessed this ninth day of June, 1922.

WILLIAM C. HIERING.
